UNITED STATES PATENT OFFICE.

WARREN S. BELLows, OF WORCESTER, MASSACHUSETTS, ASSIGNOR TO WALDEN MANUFACTURING COMPANY, OF WORCESTER, MASSACHUSETTS, A CORPORATION OF MASSACHUSETTS.

BRACE-SOCKET WRENCH.

1,072,079.

Specification of Letters Patent.

Patented Sept. 2, 1913.

Application filed August 22, 1910. Serial No. 578,360.

To all whom it may concern:

Be it known that I, WARREN S. BELLows, a citizen of the United States, residing at the city of Worcester, in the county of Worcester and Commonwealth of Massachusetts, have invented certain new and useful Improvements in Brace-Socket Wrenches, of which the following is a specification.

This invention relates to that class of wrenches wherein a bolt-receiving socket is provided with a brace for the purpose of enabling the bolts to be screwed in place more rapidly than can be done with the usual type of wrenches; and my improvements pertain to the details of construction hereinafter set forth.

Referring to the drawings forming part of this specification, Figure 1 is a side view of a brace socket wrench made in accordance with my invention. Fig. 2 is a sectional view of the head thereof. Fig. 3 is a sectional view of a modified form of the head. Fig. 4 is a sectional view on a larger scale of the grip. Fig. 5 is a detail view of the part of the brace where the grip is placed. Fig. 6 is a cross section of said grip. Fig. 7 is a sectional view on a larger scale of one of the grip-confining ferrules. Fig. 8 is a sectional view on the same scale of a part of the grip. Fig. 9 is a longitudinal section on a larger scale of the socket. Fig. 10 is an end view of the same. Fig. 11 is a side view of the part of the brace which is to be fixed in said socket. Fig. 12 is an end view of said part. Fig. 13 is a cross section of the head. Fig. 14 is a detail view showing the groove for receiving the split washer.

The main body of the brace consists of a steel rod 1 bent into the usual form shown in Fig. 1, the terminal portion 1' of which is adapted to be rotatably secured within the head 2. The latter is preferably composed of sheet metal stamped into the two cup-shaped sections 3 and 4, the upper section 3 being formed with a central recess 5 entered by the extremity of the rod 1, a steel ball 6 being preferably between, as shown in Fig. 2; the end of the part 1' being recessed to receive said ball. The lower head-section 4 is formed with an elongated opening 7 loosely fitting the brace-part 1', and a cylindrical raceway 8 for the ball bearings 9. Immediately above said balls is a solid washer 10; and above the lat-

ter, a split washer 11 thrust into the annular groove 12 (see Figs. 13 and 14). In putting this head in place, the brace part 1' is first run up through the lower head section 4 until the groove 12 is above the raceway 8; then the balls are put in, the solid washer pushed down below said groove, and the split washer pressed into place. The head-section 4 is now drawn upward to present the washers below the upper part of the raceway and thereby lock the split washer in place; the ball 6 is placed in its recess, and the head-section 3 is strongly pressed into engagement with the section 4, the fit being sufficiently tight to insure the permanent fastening of the sections together. There being almost no tool-work, this head is quite inexpensive to manufacture, while its ball bearings cause it to be well fitted for its task.

In the construction of head shown in Fig. 3, the same is of wood 14 bored and reamed out to receive the brace-part 1' and the wide wooden washer 15. The latter and a split washer 11 having been put in place upon said part, the head is placed thereon as shown; suitable glue or cement having been applied to the surfaces of said wooden members. The grip 16 consists preferably of two sheet metal sections brought together on a longitudinal plane, with their terminal edges seated in the annular grooves 17, (see Figs. 4 and 5) of the part 1'' of the rod 1. Ferrules 20 having been slipped along the brace and forced upon the ends of the split grip 16 until the detents 21 of the grip engage the recesses 22 of the ferrules. The grip is now held securely in place, being kept from end play by the grooves 17, while permitted easy rotation thereon. The grip may, of course, be split along one line alone and bent into place about the brace, but I prefer to make the same in two separate parts. The socket 25 is a casting or forging, having a hole through it, the large end of which is made to fit the size and shape of nut for which the wrench is intended. Said end 26 is shown in Figs. 9 and 10. The upper end of said hole is cylindrical to fit the rod 1, as at 27, while the remainder 29 of said hole is flat to fit the correspondingly shaped section 30 of said rod, as shown in Figs. 11 and 12. The length of the rod-section 30 is such as to permit the same to slightly more than pass through the hole 29,

so that the end of said section can be upset and thereby fastened in the socket-casting. Thus made, this brace socket wrench is very inexpensive, while at the same time it is 5 durable and efficient in use.

What I claim as my invention and for which I desire Letters Patent is as follows, to wit;

1. The combination with a round rod having two annular grooves therein, of a grip comprising two shells each having a semi-circular cross section and adapted to have 10 their ends seat loosely in said grooves, and ferrules loosely fitting said rod and inclosing said ends, each of said ferrules having recesses within it, and said shells having projections adapted to engage said recesses and 15 retain the ferrules in place thereon.
2. The combination with a round rod hav-

ing two annular grooves therein, of a grip comprising two shells each having a semi-circular cross-section and adapted to have 20 their ends seat loosely in said grooves, and ferrules loosely fitting said rod and inclosing said ends, each of said ferrules having recesses within it, and said shells having projections adapted to engage said recesses and 25 retain the ferrules in place thereon.

In testimony that I claim the foregoing invention, I have hereunto set my hand this 17th day of August, 1910.

WARREN S. BELLows.
